UNITED STATES PATENT OFFICE

DIBRELL P. HYNES AND NORTON A. MEARS, OF CHICAGO, ILLINOIS, ASSIGNEES TO
CHICAGO FORGING & MANUFACTURING CO., OF CHICAGO, ILLINOIS, A CORPORATION
OF ILLINOIS

HOOD LATCH

Application filed December 8, 1930. Serial No. 500,722.

Our invention relates to a securing means or latching device and has for one purpose the provision of a latching device or securing means for the hinged member or closure of an automobile hood. However, it is adapted for other uses or applications. One object is the provision of securing means of the type herein described which shall be efficient in use, simple to manufacture, and sightly. Another object is the provision of improved bearing means for the handle of such a locking device. Another object is the provision of a locking device including latching members within the closure, actuated by an exterior handle in response to a locking or unlocking excursion of approximately 90 degrees. Other objects will appear from time to time in the course of the specification and claims.

We illustrate our invention more or less diagrammatically in the accompanying drawings, wherein—

Figure 1 is a side elevation;

Figure 2 is a partial inside elevation on an enlarged scale;

Figure 3 is a section on the line 3—3 of Figures 1 and 2;

Figure 4 is a section on the line 4—4 of Figures 1 and 2; and

Figure 5 is a section on the line 5—5 of Figure 1.

Like parts are indicated by like symbols throughout the specification and drawings.

Referring to the drawings A generally indicates the side frame member of an automobile frame. A¹ is the hood closure which may be hinged as at A². A³ is the radiator and A⁴ the forward portion of the body of the car. A⁵ is an angle or abutment for the lower edge of the hinged member A¹.

Mounted within the radiator are any suitable keepers or latch abutments which may take the form for example of the bases B having thereon the brackets B¹ which support the keepers proper B² which may be in the form of inwardly extending rods, the whole structure being, if desired, integrally formed.

Rotatably mounted upon the inner face of the closure A¹ is the rock shaft C. It may

be mounted at its ends in the bearings C¹ and adjacent the central portion in the bearings C³ which may form part of the handle supporting plate C². C⁴ indicates a crank offset in the intermediate portion of the rock shaft, herein shown as between the bearings C³. It is shown as generally angular or V-shaped, as indicated in Figure 2. The ends of the shaft C are laterally offset as at C⁵ to form more or less arcuate or curved latching members C⁶. In the form herein shown these members C⁵ lie in planes generally perpendicular to the axis of rotation of the shaft C.

Mounted for rotation on the plate C² is the handle shaft generally indicated as D. It may carry thereon or have associated therewith the handle generally indicated as D¹ which includes the axial portion D², the portion D³ offset therefrom in general parallelism with the face of the closure A¹, and the further terminal offset D⁴, projecting inwardly toward the closure A¹ and shown in general parallelism with the axial portion D².

Secured to the inner end of the shaft D is a crank arm E. It may include the hub portion E¹, bolted or otherwise secured to the shaft D. We may for example employ a screwthreaded extension E² and a securing nut E³. Any suitable means may be employed for preventing relative rotation of the crank E and the shaft D in relation to each other. The outer end of the crank E may be apertured as at E⁴. Extending from the opposite side of the hub E¹ is a short crank or lever portion E⁴ inwardly offset as at E⁵, the portion E⁵ extending to or closely adjacent the face of the plate C². E⁶ E⁷ are movement limiting abutments formed upon the plate C², adapted to limit, by engagement with the portion E⁵, the arc of rotation of the shaft D and handle D¹.

Connecting the two cranks is the link G. At one end it is offset as at G¹, to penetrate the aperture E⁸ of the crank E. G² is a cotter pin or other suitable means for holding the offset G¹ in position in said aperture. The opposite end of the link G is formed in a loop, as at G², said loop surrounding the apex of the crank member C⁴. The loop

G^2 is somewhat inclined to or offset from the body of the link G , as shown for example in Figure 2.

In order to provide a suitable bearing for the shaft D we inwardly offset or upset the plate C^2 , as at H to form a cup. The inner rim of the cup H is provided with an inwardly extending flange H^1 , which terminates in a cylindrical flange or rim H^2 . In set in the cup H is a mating or penetrating cup generally indicated as J which includes a cylindrical portion J^1 seated within the cup and an inner peripheral cylindrical flange J^2 , of a diameter proper to receive the shaft D . We thus provide a compound bearing formed of two cylindrical sleeves more or less spaced apart, the total length of such bearing being preferably equal to or even exceeding the diameter of the shaft D , whereby proper lateral support is afforded the shaft.

The closure A^1 is apertured as at K , in order to permit the extension therethrough of the cup J or the cylindrical bearing J^1 .

We may provide an ornamental and protecting boss K^1 which includes a peripheral portion K^2 penetrating between the inner face of the closure A^1 and the opposed outer face of the plate C^2 . K^3 indicates an inwardly turned portion of the boss which conforms closely to the exterior diameter of the handle D^1 . If desired the boss may be adapted to take a finish corresponding to the finish of the handle D^1 .

It will be realized that whereas we have described and shown a practical and operative device, nevertheless many changes may be made in size, shape, number and disposition of parts without departing from the spirit of our invention. We wish our drawings, therefore, to be taken as in a broad sense illustrative and diagrammatic rather than as limiting us to the features herein described and shown.

It will be understood, in particular, that a variation in the arc of rotation of the handle may be made without departing from the spirit of my invention and where we specify "approximately a quarter turn" or "approximately 90 degrees", we wish it to be understood that this language is intended to cover a reasonable variation in either direction from 90 degrees.

The use and operation of our invention are as follows:

Assume that in the locking position the exterior handle D^1 is in horizontal position with the locking members C^5 engaging the interior keepers. Preferably, when in such position the handle may be an open ended loop with the open end projecting rearwardly as at D^4 . This carries out the stream line idea and fits into the general design of the modern car. To unlock the closure the operator rotates the handle by pulling up on it

and lifting or turning it as far as it will go. It would be grasped from underneath on the left hand side of the car, and from above on the right hand side of the car, since the handle in each case projects toward the rear of the car. In either case an upward pull releases the latch. This upward pull is effective to rotate the handle through an arc of approximately 90 degrees. Any suitable stop means are employed for limiting the rotation at or near 90 degrees, for example the stops E^6 E^7 . At that point the handle will not rotate further and continual upward movement of the operator's hand will serve to lift the door of the hood. However, the parts are so proportioned that when the complete 90 degree excursion is made, the locking members are rotated into unlocking position. We obtain this result by employing the interior crank E associated with the handle and the interior crank C^4 associated with the rock shaft, the relative effective lengths of the two cranks being such that a rotation of the handle crank through approximately 90 degrees effects whatever arc of rotation of the rock shaft is necessary in order to move the locking members from complete locking position to completely free position. Hence the crank E greatly exceeds the crank C^4 in length.

Note that when in the locking position the crank E is thrust over center and the spring of the rock shaft therefore holds it or tends to hold it in locked position, and against the stop E^7 . On the other hand, when the exterior handle D^1 is rotated to the opposite limit of its arc of movement the stop E^6 is contacted. In the particular form herein shown the crank is provided with a short arm E^4 at the opposite side of its axis of rotation, which short arm has an offset portion E^5 extending outwardly toward the inner face of the hood and engaging the stops E^6 E^7 to limit the excursion of the crank and the rotation of the handle to the predetermined arc of approximately 90 degrees.

We use a simple link G between the two cranks, which may be a generally straight rod having one end looped around the offset integral crank portion C^4 of the rock shaft. The other end may be turned at an angle as at G^1 , in order to penetrate the aperture E^3 in the outer end of the handle crank. The loop G^2 at the bottom of the link is somewhat offset or inclined, in order to obtain the proper angle of thrust upwardly and downwardly when the connection between the link and the handle crank is laterally offset as the handle crank is rotated. During its movement, and until it actually reaches and passes center, the point of connection between the handle crank and the link is of course laterally offset from the center of rotation of the crank, as shown in dotted line in Figure 2.

We find it efficient to provide a more or less V-shaped loop C^4 as a crank for the rock

shaft. The bottom loop G^2 of the link engages the relatively sharp end of this crank and in practice, the parts being proportioned as they are, this keeps the connection between 5 link and rock shaft crank properly located and the link cannot in practice slide down the sides of the crank. This guiding is also in part effected by the fact that the top portion G^1 of the link which is bent to pass through 10 the aperture E^3 prevents rotation of the link as a whole and therefore prevents its turning as it must if it were to slide down or along either side of the rock shaft crank offset. 15 The offset locking members C^5 at the ends 20 of the rock shaft lie in planes generally perpendicular to the axis of rotation of the rock shaft. The portion lying in such plane is more or less curved or arcuate in such fashion as to form a species of hook which is upwardly thrust under the keeper B^2 by rotation of the rock shaft. The parts are so proportioned that these hooks engage the keepers before the end of the locking rotation of the 25 handle, in such fashion that the torsion of the rock shaft and the resilience of the locking members will lock the handle crank in position after it has passed across center. Thus it is yieldingly held against the stop E^6 which 30 limits its locking rotation. The arcuate form of the terminal locking members is such that they tend, in response to their yielding thrust, to draw the lower edge of the hood closure both inwardly and downwardly, thus giving the desired tight locking effect. 35 In order to prevent displacement of the axis of rotation of the handle for example because of torsion of the shaft and locking means we upset the plate C^2 through which the handle 40 shaft passes to form the cup H , which receives the cup J . The two cups support the two bearing surfaces H^2 , J^2 , separated by say a quarter of an inch or more. The total length for example of the combined bearing surface 45 so formed may be $\frac{3}{8}$ inch and may equal or even preferably exceed the diameter of the shaft D which passes therethrough. The result is greatly to limit the tendency of the shaft to be displaced. A further assistance 50 is given by the inwardly projecting end E^5 , which slides on the rear of the plate, and, when the parts are assembled, provides a further very substantial reinforcement to prevent displacement of the shaft. In actual 55 practice it may be set up with a slight clearance but a very small distortion will bring it into actual contact with the inner surface of the plate to which it is opposed. In effect the exterior bearing J^2 provides a bearing to compensate or to prevent displacement by 60 the thrust or weight upon the handle, just as the inner bearing H^2 prevents displacement from the application of force to the inner handle crank. The composite bearing so formed may lie partly within and partly 65 without the hood wall.

We claim:

1. A latching device for automobile hoods or the like, which includes a plurality of latch abutments positioned within the hood and laterally inwardly spaced from the hood closure when it is in closed position, a rock shaft mounted upon the interior of said hood, said shaft having an intermediate crank, offsets associated with said rock shaft and adapted to be opposed to said abutments in response to a locking rotation of said rock shaft, a handle mounted upon the exterior of the hood for rotation about an axis generally perpendicular to the face of the hood, and connecting means intermediate the exterior handle and the crank shaft including means proportioned to impart to the crank shaft a rotation sufficient to move the offsets from unlocking to locking position, in response to a rotation of the exterior handle through an arc substantially less than the arc of locking rotation of the rock shaft. 70 75 80 85

2. A latching device for automobile hoods or the like, which includes a plurality of latch abutments positioned within the hood and laterally inwardly spaced from the hood closure when it is in closed position, a rock shaft mounted upon the interior of said hood, the ends of said rock shaft being offset to form cranks lying in planes generally perpendicular to the axis of rotation of the rock shaft, said cranks being adapted to be opposed to said abutments in sliding locking relationship, in response to a locking rotation of said rock shaft, and means for rotating said rock shaft into and out of locking position, including an exterior handle and an actuating connection between said exterior handle and the rock shaft the keeper engaging portions of said cranks lying, when in locking position, above the axis of rotation of the rock shaft. 90 95 100 105

3. A latching device for automobile hoods and the like, which includes a latch abutment positioned within the hood and laterally inwardly spaced from the hood closure when it is in closed position, a rock shaft mounted upon the interior of said hood, latching means, associated with said shaft, adapted to engage said abutment, said shaft having a crank, an exterior handle mounted upon said hood, an interior crank associated therewith, the handle and the crank being rotatable about an axis generally perpendicular to the face of the hood, and a link connection between said crank and the rock shaft crank, the effective length of the handle crank substantially exceeding the effective length of the rock shaft crank. 110 115 120

4. A latching device for automobile hoods and the like, which includes a latch abutment positioned within the hood and laterally inwardly spaced from the hood closure when it is in closed position, a rock shaft mounted upon the interior of said hood, latching means, associated with said shaft, adapted to 125 130

engage said abutment, said shaft having a crank, an exterior handle mounted upon said hood, an interior crank associated therewith, the handle and the crank being rotatable about an axis generally perpendicular to the face of the hood, connecting means between the handle crank and the rock shaft crank, including means proportioned to rotate said rock shaft from locking to unlocking position in response to a rotation of said handle of approximately 90 degrees, and limiting means adapted positively to limit the rotation of said handle and handle crank, at the opposite ends of its arc of rotation.

5. A latching device for automobile hoods and the like, which includes a latch abutment positioned within the hood and laterally inwardly spaced from the hood closure when it is in closed position, a rock shaft mounted upon the interior of said hood, latching means, associated with said shaft, adapted to engage said abutment, said shaft having a crank, an exterior handle mounted upon said hood, an interior crank associated therewith, the handle and the crank being rotatable about an axis generally perpendicular to the face of the hood, connecting means between the handle crank and the rock shaft crank, effective to rotate said rock shaft from locking to unlocking position in response to a rotation of said handle of approximately 90 degrees, limiting means adapted positively to limit the rotation of said handle and handle crank, at the opposite ends of its arc of rotation, including a member outwardly extending from the axis of rotation of the crank and stops positioned inwardly of the plane of the inner face of the hood, adapted to be engaged thereby.

6. A latching device for automobile hoods and the like, which includes a latch abutment positioned within the hood and laterally inwardly spaced from the hood closure when it is in closed position, a rock shaft mounted upon the interior of said hood, latching means, associated with said shaft, adapted to engage said abutment, said shaft having a crank, an exterior handle mounted upon said hood, an interior crank associated therewith, the handle and the crank being rotatable about an axis generally perpendicular to the face of the hood, and a link extending between said crank and the rock shaft, one end of said link being offset to penetrate the handle crank, the handle crank being apertured to receive it, the other end being formed in an eye to surround the rock shaft crank.

7. A latching device for automobile hoods and the like, which includes a latch abutment positioned within the hood and laterally inwardly spaced from the hood closure when it is in closed position, a rock shaft mounted upon the interior of said hood, latching means, associated with said shaft, adapted to engage said abutment, said shaft having a

crank portion offset from the intermediate portion of said shaft, an exterior handle mounted upon said hood, and an interior crank associated therewith, the handle and the crank being rotatable about an axis generally perpendicular to the face of the hood, and a link connecting the handle crank and the rock shaft crank, said link including an eye surrounding the rock shaft crank portion, said eye being bent out of alignment with the body of the link.

8. A latching device for automobile hoods and the like, which includes a latch abutment positioned within the hood and laterally inwardly spaced from the hood closure when the closure is in closed position, a rock shaft mounted upon the interior of said hood, latching means, associated with said shaft, adapted to engage said abutment, an exterior handle, means operated by said handle, for rotating said rock shaft, including a shaft associated with said handle and penetrating the hood, and a plurality of axially disposed cylindrical bearings in which said shaft rotates and a supporting plate, secured to the hood, one of said cylindrical bearings being upset in said supporting plate.

9. A latching device for automobile hoods and the like, which includes a latch abutment positioned within the hood and laterally inwardly spaced from the hood closure when the closure is in closed position, a rock shaft mounted upon the interior of said hood, latching means, associated with said shaft, adapted to engage said abutment, an exterior handle, means operated by said handle, for rotating said rock shaft, including a shaft associated with said handle and penetrating the hood, and a plurality of axially disposed cylindrical bearings in which said shaft rotates a supporting plate, secured to the hood, one of said cylindrical bearings being upset in said supporting plate, and a bearing member, in which said other cylindrical bearing is formed, mounted on said plate.

10. A latching device for automobile hoods and the like, which includes a latch abutment positioned within the hood and laterally inwardly spaced from the hood closure when the closure is in closed position, a rock shaft mounted upon the interior of said hood, latching means, associated with said shaft, adapted to engage said abutment, an exterior handle, means operated by said handle, for rotating said rock shaft, including a shaft associated with said handle and penetrating the hood, and a plurality of axially disposed cylindrical bearings in which said shaft rotates and additional means for preventing misalignment of the axis of said shaft in response to torsion of the rock shaft when in locking position.

11. A latching device for automobile hoods and the like, which includes a latch abutment positioned within the hood and laterally in-

- wardly spaced from the hood closure when the closure is in closed position, a rock shaft mounted upon the interior of said hood, latching means, associated with said shaft, 5 adapted to engage said abutment, an exterior handle, means operated by said handle, for rotating said rock shaft, including a shaft associated with said handle and penetrating the hood, and a plurality of axially disposed 10 cylindrical bearings in which said shaft rotates and additional means for preventing misalignment of the axis of said shaft, including a member extending outwardly from the shaft and adapted to engage the inner 15 face of the hood in response to torsion of the rock shaft.
12. A latching device for automobile hoods and the like, which includes a latch abutment positioned within the hood and laterally inwardly spaced from the hood closure when it is in closed position, a rock shaft mounted upon the interior of said hood, latching means, associated with said shaft, adapted to engage said abutment, said shaft having a 25 crank, an exterior handle mounted upon said hood, an interior crank associated therewith, the handle and the crank being rotatable, about an axis generally perpendicular to the face of the hood, and connecting means between the handle crank and the rock shaft crank, effective to rotate said rock shaft to and from locking position in response to a rotation of said handle of approximately 90 degrees, including an abutment adapted to 30 limit further rotation of the handle crank, the torsion of the rock shaft being adapted to maintain the parts in locked position in relation to said abutment.
13. A latching device for automobile hoods and the like, which includes a latch abutment positioned within the hood and laterally inwardly spaced from the hood closure when the closure is in closed position, a rock shaft mounted upon the interior of said hood, 40 latching means, associated with said shaft, adapted to engage said abutment, an exterior handle, means operated by said handle, for rotating said rock shaft, including a shaft associated with said handle and penetrating the hood, and a plurality of axially disposed 45 cylindrical bearings in which said shaft rotates and a supporting plate, secured to the hood, one of said cylindrical bearings being upset in said supporting plate, said supporting plate being also provided with bearing 50 means for rotatably receiving the rock shaft.
14. A latching device for the double hinged closure of an automobile hood, which includes latch abutments positioned within and spaced laterally inwardly from the closure when the closure is in closed position, a rock shaft mounted upon the interior of the closure and latching means between said shaft and said abutments, said shaft having a 55 crank, an exterior handle mounted upon said 60 65
- hood for rotation about an axis vertically offset from the axis of rotation of the rock shaft, and an interior crank associated with said handle, the handle crank being of substantially greater effective length than the rock shaft crank, and connecting means intermediate the handle crank and the rock shaft crank to rotate the rock shaft from locking to unlocking position in response to a rotation of said handle through substantially a quarter turn, and limiting means effective to limit the rotation of said handle to approximately a quarter turn.
- Signed at Chicago, in the county of Cook, and State of Illinois, this 5th day of December, 1930.
